CLAIM

The ornamental design for a display screen with graphical user interface or portion thereof, as shown and described.

DESCRIPTION

FIG. 1 is a front view of the first embodiment of the display screen with graphical user interface or portion thereof, showing our new design.

FIG. 2 is a front view of the second embodiment of the display screen with graphical user interface or portion thereof, showing our new design; and,

FIG. 3 is a front view of the third embodiment of the display screen with graphical user interface or portion thereof, showing our new design.

The outermost broken line perimeter showing the display screen and the broken lines within showing portions of the graphical user interface, including the broken line text, are provided for the purpose of illustrating portions of the article and forms no part of the claimed design.

1 Claim, 3 Drawing Sheets
